BY *Howard C. Thompson*
ATTORNEY

UNITED STATES PATENT OFFICE

ERIC W. ERICSSON, OF BROOKLYN, NEW YORK

KNIFE

Application filed January 21, 1930. Serial No. 422,251.

This invention relates to knives, erasers and the like; and the object of the invention is to provide a knife of the class specified comprising a handle member consisting of 5 relatively movable parts and a blade member adapted to be arranged between the separate parts of the handle member and retained in different positions with respect thereto as well as being readily detachable therefrom 10 whereby new blade members may be substituted for old or worn out blades; a further object being to provide means for pivotally coupling the separate parts of the handle member at one end thereof to permit the 15 separation of said parts with means adjacent the other end of said parts for clamping the same together and for retaining the blade in connection therewith; a further object being to so fashion the separate parts of the 20 handle member at the blade end of the knife as to conform with the contour of the shank of the blade in the several positions thereof to key the same against movement independently of the first named securing means; and 25 with these and other objects in view, the invention consists of the knife of the class and for the purpose specified which is simple in construction, efficient in use, and which is constructed as hereinafter described and 30 claimed.

The invention is fully disclosed in the following specification, of which the accompanying drawing forms a part, in which the 35 separate parts of my improvement are designated by suitable reference characters in each of the views, and in which:

Fig. 1 is a side view of a knife made according to my invention showing the blade in position for use.

Fig. 2 is a section on the line 2—2 of Fig. 1.

Fig. 3 is a section on the line 3—3 of Fig. 1.

Fig. 4 is a side view of the opposite side of the handle of the knife from that shown in Fig. 1, and illustrating the blade in inoperative position; and,

Fig. 5 is a section on the line 5—5 of Fig. 4.

In the drawing, I have shown one con-

struction of knife for carrying my invention into effect, and in the several figures, 10 represents the handle member and 11 the blade. The handle member 10 in the construction shown is fashioned from two sheet metal parts 12 and 13, the handle end 14 of which is concavo convex in cross sectional form so that the marginal edges will abut as indicated at 15, note Fig. 2 of the drawing, and the parts 12 and 13 are pivoted together as seen at 16 at the end portion 14 whereas the jaw ends 17 of the parts 12 and 13 are relatively flat except that the part 12 has a recess on its inner surface formed by stamping the material of said part outwardly in accordance with the contour seen at 18 in Fig. 1 of the drawing so as to provide a recess 19 of an outline corresponding to that of the shank end 20 of the blade 11. In like manner, the jaw end of the part 13 is pressed outwardly 70 in the manner indicated at 21, note Fig. 4 to form a recess to receive the shank of the blade 11 when said blade is supported in the position indicated in Fig. 4 of the drawing with the cutting end 22 arranged within and between the parts 12 and 13.

The outwardly pressed portions 18 and 21 serve to key the blade 11 against movement relatively to the handle member 10 or the separate parts thereof when the blade is in 75 the position shown in Figs. 1 and 4, and the jaw ends 17 of the parts 12 and 13 are clamped together by a screw 23 in threaded engagement with the part 13, and the milled head 24 of which operates to move the part 12 toward the part 13 to securely clamp the blade 11 in 80 position, it being understood that the blade 11 has an aperture through which the screw 23 passes as clearly seen in Fig. 2 of the drawing.

In the use of the device, it will be understood that the blade 11 is placed within and between the jaw end 17 of the parts 12 and 13 in the manner shown in Figs. 1 and 2 of the drawing and the screw 23 moved into position to securely clamp the blade within and between the adjacent faces of said parts, and the knife is now in position for use. At this time, it will be understood that the blade end 85 of the knife may be of any desired contour 90

or size, the handle member or the parts thereof being fashioned to correspond with that of the blade, and when it is desired to discontinue the use of the knife, the screw 23 is loosened sufficiently to allow the blade to be swung into the position shown in Fig. 4 with the blade end 22 within and between the parts 12 and 13 and the boundaries thereof, after which the screw is again tightened to retain said blade against displacement, and in this position the blade may be carried about.

Whenever desired, a new blade or a different type of blade may be coupled with the handle member by removing the screw and by swinging the handle members on their pivot 16. The latter is not absolutely necessary as the opening in the blade may extend through one wall thereof to form a notch type aperture as is customary in other types of tools of this class.

It will also be understood that while I have described my invention as pertaining to knives, scrapers and the like, it will be understood that any kind or class of blade may be mounted in connection with the handle member such for example as chisels, saws and the like, the distinctive feature of my invention being to provide a cheap and yet strong and durable handle member so constructed as to permit the mounting of tools of various kinds and classes in connection therewith, all having a shank of common contour facilitating the mounting of the tool in connection with the handle member. Various changes in and modifications of the construction herein shown and described may be made within the scope of the appended claims without departing from the spirit of my invention or sacrificing its advantages.

Having fully described my invention, what I claim as new and desire to secure by Letters Patent, is:

1. A knife of the class described comprising two elongated, sheet metal handle members pivotally coupled together at one end to permit separation of said handle members in the plane of the abutting faces thereof, the other ends of the handle members terminating in jaws in connection with which a blade is adapted to be movably supported, a screw passed through said jaws and blade for clamping the blade in different positions of adjustment within and between said jaws, and one jaw having an outwardly pressed portion projecting beyond the outer face of the jaw and of a contour corresponding to that of the shank of said blade to retain the blade against movement when in projected position.

2. A knife of the class described comprising two elongated, sheet metal handle members pivotally coupled together at one end to permit separation of said handle members in the plane of the abutting faces thereof, the other ends of the handle members terminat-

ing in jaws in connection with which a blade is adapted to be movably supported, a screw passed through said jaws and blade for clamping the blade in different positions of adjustment within and between said jaws, one jaw having an outwardly pressed portion of a contour corresponding to that of the shank of said blade to retain the blade against movement when in projected position, and the other jaw member having an outwardly pressed portion conforming with the contour of a part of the shank of the blade to retain the blade against movement with respect to the jaws when the same is contained within the jaws and handle members in inoperative position, and the central portions of the handle members being pressed outwardly to form a chamber within and between the handle members and peripheral flanges, adjacent faces of which abut.

In testimony that I claim the foregoing as my invention I have signed my name this 17th day of January, 1930.

ERIC W. ERICSSON.
